UNITED STATES PATENT OFFICE.

WILLIAM G. VENARD, OF LOS ANGELES, CALIFORNIA.

SCAFFOLD STRUCTURE.

Application filed February 16, 1927. Serial No. 168,666.

This invention relates to building-scaffold structures and more especially to a knock-down, portable, scaffold equipment.

An object of the invention is to provide 5 a scaffold system of interlocking columns and girders adapted to be erected stage on stage as the wall of a building is built up by workmen on the scaffold platform.

Another object is to provide a step-by-step 10 built scaffold apparatus incorporating a fabrication of disconective members which provide a work platform, a material trackway and an elevator carriage tower.

A further object is to provide a column 15 scaffold in distinction from an overhead suspension apparatus scaffold, and to provide means for attachment to the columns of the system and whereby deck equipment may be raised or lowered, in stages of operation.

20 Additional objects, advantages and features of the invention will be made manifest in the following specification of the herewith illustrated embodiment of the invention; it being understood that variations, modifications 25 and adaptations may be resorted to within the spirit, scope and principle of the invention as it is more directly hereinafter claimed.

Figure 1 is a front elevation of the scaffold. 30 Figure 2 is a plan of the scaffold.

Figure 3 is an elevation of a top-header applied to the tops of tower forming columns.

Figure 4 is a detail of a column-top cable hook of an elevator means.

35 Figure 5 is an elevation of a column unit.

Figure 6 is an elevation and partial section of an elevator element, showing platform boards laid thereon.

40 Figure 7 is an elevation of an elevator drum as adapted to a long elevator element.

Figure 8 is a detail of a winch lock.

Figures 9 and 10 show a flexible rail joint to allow a change of angle of connected rail sections.

45 Figures 11 and 12 are elevation and plan views of portions of longitudinal girders of the frame.

Figure 13 is a plan of a girder nest; its column being in cross-section.

50 Figure 14 is a plan of a portion of a cross-girder.

In the present system a suitable number of duplicate, interchangeable columns 2 are each provided with spaced rests or nests 3

55 each having a plurality of angularly spaced, conical seat forming sockets 4 open at the top

and at the outer side for the reception of wedge plugs 5 provided at the ends of longitudinal girders 6 and of cross girders 7, the latter being here shown as of channel-iron, 60 to carry a load.

Preferably the connecting plugs 5 are attached to the girders by means which allow of a desired or necessary change of angle of the latter as indicated by dotted lines in Fig. 11. 65 To that end the plug 5 has a shank with a toothed cheek 5^a to clamp against a friction part or tongue 5^b at the end of the girder. The parts 5^a—5^b are adapted to be firmly clamped at any desired angle by a bolt 8. 70

The bottom of each plug 5 has a stout hook 9 and each socket nest 3 has a set of top hooks 10.

In practice, two or more series of the columns 2 are set up at given distance and spacing along a proposed building wall line and the first course of columns 2 is braced by applying the girders 6 and 7 to the sets of nests. 75 As courses of the columns are successively superimposed, guy lines or rods 12 are run diagonally to connect with hooks 10 and hooks 9 of the coordinate parts. 80

The lower end of each column 2 has a fixed sleeve 13 to telescope over the top of the next lower course column; these being built up in 85 any desired number.

As shown in plan, Fig. 2, the columns may be set in three series along a wall line and an outer group of columns may be disposed and built up to form an elevator 90 carriage shaft having vertical rails 14 for its carriages, one of which is shown at E. In this tower or shaft group the tops of the columns are capped by headers 15 having cups 16 to set over the ends of the columns. Suitable carriage lifting rigging is mounted on the headers 15. 95

As course after course of the scaffold frame parts 2—6—7 is assembled the guys 12 are applied and tightened up, as by turn-buckles 12^a and in some cases the guys have take-up chains 12^b. 100

The sockets 4 have wide side openings to allow for angular relational position of the applied girders, as indicated in Fig. 13. 105

Means are included for supporting and vertically adjusting appropriate decking equipment, as workmen's platform and car trackway, and here includes transversely disposed elements 20 consisting of inverted channel-iron elements which have bottom straps 21 to slidably support a spacer 22, in the ele- 110

ment, and which may be bolted in desired extended position by a bolt 23 to steady the parts in a desired position out from the wall being erected, and carry flooring for workmen.

Each elevator 20 has a set of hoist drums 25 with suitable hand levers 26 for operating the drums to wind or slack off a respective hoist tackle or cable 27 having a hook 28 at its free end to hook over the top, open end of the tier column, as is shown in Fig. 5.

Different lengths of elevator elements may be employed. Short lengths 20 are used when only a workmen's platform P is to be hung on the tiers. Where a triple series of tiers are used so as to provide for a trackway T, outside of the platform, then longer beams 20^a are employed. The drums 25 have cradles 29 swivelled on vertical pivots 30 on the base 31, which has loops 32 to slide onto the beam 20 and fasten by a bolt 33. The loops 32 are so spaced as to straddle the sides of the longer beams 20^a when applied thereto with the base 31 in a cross-wise position. In such case the cradle and drum 25 are turned across the base. Bolts 34 hold the loops to the beam 20^a.

The trackway includes sleepers 35 carrying rail sections 36 whose contiguous ends are spliced by side links 37 and pivot bolts 38, which allow of some angular deflection up or down as may be advantageous in erecting the scaffold.

The scaffold may be installed in straight or angle or curved lines of columns.

What is claimed is:

1. A scaffold system including tiers of columns, and hoistable deck apparatus including elevator elements with windable hitches attachable to respective pairs of tiers, said elements having telescopic steadyng spacers to stand the deck out from the wall.

2. A scaffold system including tiers of columns, means interlocking the columns, elevator elements for decking equipment, and winches having bases with loop parts to telescopically receive said elements, the winches being swivelled on their bases for angular adjustment.

3. A scaffold system including series of columns, girders interlocking the columns, coordinate columns and girders, and deck carrying elevator elements transversely arranged above the highest girders so as to be adjustable upward thereover and having hitch means for attachment to the tops of the tiers; said elements hanging free from the near columns.

4. A scaffold system including tiers of columns, means connecting tiers transversely to form laterally spaced series, guys for the tiers, and a platform vertically adjustable between series of the tiers and having hoist tackle with carriers swinging free of the columns and hitchable to cross sets of the

tiers the tackle being transferable from column to column of the erected system.

5. A scaffold system including an inner, an outer and an intermediate series of column tiers, girders interlocking with respective columns along and across the series, and elevator elements extending across the series in a position above the highest girders and carrying an inner platform and an outer trackway substantially in a common plane; whereby the platform and tracks are uniformly elevated, as building progresses, and material from vehicles on the tracks may be transferred to different positions along the coplanar platform.

6. In a scaffold system, a platform structure including a sectional telescopic platform carrying beam, winch bases having aligned cross loops in which the beam is slidably mounted, and a suspending winch including a cradle turnably connected to the top of its base and adapted for longitudinal and transverse adjustment as to the base when mounted on a beam.

7. In a scaffold system, a suspending winch having a cradle and a base with a pair of transversely disposed, longitudinally spaced and coaxial loops on its bottom, said loops being adapted to telescopically receive a scaffold beam or to embrace the sides of an interposed beam straddled by the base, said cradle being pivoted on the base; whereby the cradle may be set longitudinally of a beam irrespective of the position of the base on the beam.

8. A scaffold system including tiers of columns in inner and outer series, girders detachably interlocked with coordinate columns, transversely disposed, elevator elements disposed at the sides of respective columns and free thereof, and means carried by said elements hitchable to the open tops of respective columns for vertically shifting the elevators.

9. In a scaffold system, a winch means including a base device applicable to a platform carrying beam to lie either along or across the beam, and a cradle carrying a rope drum and being rotatively attached to the base so as to be set either along or across the base to lie along the relative beam.

10. A building scaffold system having in combination, spaced series of columns, forming an inner way for a workmen's platform and an outer way for a track along the scaffold, a shaft for skip carriages, elevator elements extending across the series and carrying a platform and a track means in parallelism and common plane for a vehicle operative along the track means, and a skip carriage operative on the shaft to convey material to the vertically elevated track means and platform on said elements.
